UNITED STATES PATENT OFFICE.

HENRY J. S. MACKAY, OF HYDE, ISLE OF WIGHT, ENGLAND, ASSIGNOR TO THE BAB-COCK & WILCOX COMPANY, OF BAYONNE, NEW JERSEY, A CORPORATION OF NEW JERSEY.

BOILER FURNACE.

Application filed August 21, 1920. Serial No. 405,041.

To all whom it may concern:

Be it known that I, HENRY J. S. MACKAY, a subject of the King of Great Britain, residing at Rosemount, Bellevue Road, Hyde, 5 Isle of Wight, in the county of Hampshire, England, have invented certain new and useful Improvements in Boiler Furnaces, of which the following is a specification.

This invention relates to boiler furnaces 10 and has for its object to provide an improved construction and arrangement of such furnaces particularly adapted for use for burning wood, megass and like fuel.

One of the objects of the invention is to 15 provide a sloping grate on which the fuel may be dried and partly consumed and a horizontal grate on which the combustion may be completed, under forced draft, if desired.

Another object of the invention is to 20 provide a roof over such grates designed so that the heat from the point of complete combustion may be reflected and radiate to the fuel on the sloping grate to drive off excess 25 moisture from such fuel.

Another object of the invention is to 30 provide such a furnace with a charging hopper arranged so that the entrance of air to the furnace, while charging it, is prevented.

With these and other objects in view, my 35 invention comprises the arrangement hereinafter described and pointed out in the appended claims.

The invention is illustrated in the accompanying drawings in which Figure 1 is a 40 sectional elevation of a boiler furnace constructed in accordance with the invention; Fig. 2 is a plan view, partially broken away of the furnace and setting of Fig. 1, and Fig. 3 is a section taken along the plane of 45 the line 3—3 of Fig. 1.

In the illustrated form, the furnace is provided near its upper end with a charging hopper *a* consisting of a wrought iron or 45 steel chute with a top cover *b* connected by means of a wire rope or the like with a guillotine door *c* located in the furnace end of the hopper in such manner that the guillotine door closes at the moment the cover of 50 the hopper is opened to charge the same with fuel and no air can be admitted to the furnace. Beyond the guillotine door within the furnace is disposed a sloping grate *d* which, in the form illustrated, is provided

with steps. On this grate the fuel moves 55 by gravity, being dried and partly consumed in its downward path. In my preferred form, at the lower end of the step grate *d* are disposed blast bars *e* formed with a plurality of openings *B* on their upper surfaces and connected by air pipes *f*, *f'*, supplied with air under pressure by a fan (not shown) located outside the furnace. Preferably intermediate these blast bars are disposed a series of movable grate bars, 60 which, in the illustrative form, are rocking bars *g* adapted to rock on pivots *h* and operable by means of arms *i* and a connected link *j* extending outside the furnace by a handle *k*. Above the step grate *d* is located 65 a sloping arch *l* which projects into the main combustion chamber of the boiler, and for this reason is capable of radiating sufficient heat to drive off superfluous moisture from the fuel passing over the step 70 grate.

The lower portion of the furnace consisting of the movable bars forming a horizontal grate located adjacent to the bridge wall as illustrated, and forced draught bars 80 serves to deal with the charcoal formed in the furnace due to the formation of fine ash around the wood fuel, which fine ash prevents the necessary oxygen for combustion coming into contact with the wood or the 85 like to be burned. By means of the movable bars, the mixture of carbon and ash is agitated so as to free the surface of the carbon and by means of the forced draught bars, the necessary amount of oxygen is provided 90 to ensure perfect combustion.

What I claim and desire to secure by Letters Patent of the United States is:—

1. In a boiler furnace for burning wood, megasse and the like, a sloping grate, a horizontal grate having movable parts and located at the lower end of the sloping grate and arranged to receive fuel therefrom, pipes leading from the front of the furnace for supplying forced draft to the horizontal 95 grate only, and a sloping roof extending over both the sloping and the horizontal grates for directing the radiated heat from the fuel bed on the horizontal grate against the fuel bed on the sloping grate. 100

2. In a furnace for burning wood, megasse and the like, a sloping grate, a horizontal grate at the lower end of the sloping grate

- and arranged to receive fuel therefrom, pipes leading from the front of the furnace for supplying forced draft to the horizontal grate only, and a sloping roof arranged to 5 provide a chamber increasing in height from the front to the rear of the furnace and extending over both the sloping and the horizontal grates for directing the radiated heat from the fuel bed on the horizontal grate 10 against the fuel bed on the sloping grate, the horizontal grate comprising stationary forced blast bars and rocking bars, whereby the fuel on the horizontal grate is kept free of ash from the fuel and air is supplied to 15 the fuel to complete combustion thereof.
3. In a furnace for burning wood, megasse and the like, a bridge wall, a sloping grate, a horizontal grate located adjacent the said bridge wall at the lower end of the 20 sloping grate and arranged to receive fuel therefrom, pipes leading from the front of the furnace for supplying forced draft to the horizontal grate only, and a sloping roof arranged to provide a chamber increasing in height from the front to the rear of the furnace and extending over both the sloping and the horizontal grates for directing the radiated heat from the fuel 25 bed on the horizontal grate against the fuel bed on the sloping grate, the horizontal grate comprising stationary forced blast bars and rocking bars, whereby the fuel on the horizontal grate is kept free of ash from the fuel and air is supplied to the fuel to complete combustion thereof.

bed on the horizontal grate against the fuel bed on the sloping grate, the horizontal grate comprising stationary forced blast bars and rocking bars, whereby the fuel on the horizontal grate is kept free of ash from the fuel and air is supplied to the fuel to 30 complete combustion thereof.

4. In a furnace for burning wood, megasse and the like, a bridge wall, a stationary sloping grate, a horizontal grate located adjacent the said bridge wall at the lower end of the sloping grate and arranged to receive fuel therefrom, pipes leading from the front of the furnace for supplying forced draft to the horizontal grate only, and a sloping roof arranged to provide a chamber increasing in height from the front to the rear of the furnace and extending over both the sloping and the horizontal grates for directing the radiated heat from the fuel bed on the horizontal grate against the fuel bed on the sloping grate, the horizontal grate comprising stationary forced blast bars and rocking bars, whereby the fuel on the horizontal grate is kept free of ash from the fuel and air is supplied to the fuel to 40 complete combustion thereof.

H. J. S. MACKAY.
